TIME ACTUATED DIAL CONTROL FOR
RADIO RECEIVING SETS

Christian Petersen, Detroit, Mich.

Application May 20, 1931, Serial No. 538,813

5 Claims. (Cl. 250—20)

This invention relates to improvements in time actuated dial controls for radio receiving sets. It is an object of the invention to provide a time actuated dial control which, when once set, 5 will turn a variable condenser to various desired settings consecutively at predetermined intervals of time, so that the desired programs from the same or different broadcasting stations will be obtained over prolonged periods. 10 Another object of the invention is to provide such a control which may consist of any desired number of units so that the controls, when once set, will operate the variable condenser for long or short periods of time. 15 Another object of the invention is to provide such a control wherein means are provided for manually returning the drum to its initial position, and to mark the position of the drum so that it may immediately be seen when the drum 20 has been returned to its initial position.

A further object of the invention is to provide such a control mechanism which is relatively cheap and simple to install and operate. With these and other objects and advantages 25 in view which will become apparent as the specification proceeds, the invention is hereinafter more fully described with the aid of the accompanying drawings, in which:

Figure 1 illustrates a plan view of the invention connected to a conventional variable condenser, and also showing a diagram of the preferred arrangement of wiring.

Figure 2 is a front view partly in section, and is taken on the line 2—2 of Figure 1.

Figure 3 is an end view thereof.

Figure 4 is an enlarged section on the line 4—4 of Figure 1.

Figure 5 is an enlarged detail partly in section showing some of the dials and contact discs, and

Figure 6 is an enlarged view on the line 6—6 of Figure 1.

Figure 7 is a wiring diagram.

Referring to the drawings, 1 designates a conventional form of variable condenser on which an ordinary dial 2 is mounted on the condenser shaft 3. Secured to the latter are one set of plates 4, and 5 denotes the stationary plates. For the successful operation of my device in its preferred form it is necessary that the shaft 3 be free to 50 rotate repeatedly in the same direction. It is therefore necessary to provide a means of connecting a wire 6 to the shaft 3 so that rotation of the latter is permitted. A preferred means of doing this consists of providing a contact ring 7 on the shaft 3 which is constantly wiped by

brushes 8. 9 indicates a second wire to the stationary plates 5. The wires 6 and 9 are connected in any desired manner to other portions of the receiving set in a conventional manner.

Suitably mounted as in bearings 10 and 11 is 5 a spindle 12 which is in axial alignment with the shaft 3, and connected thereto by an insulating coupling 13. Fixed on the spindle 12 are a plurality of spaced dials 14 having markings 14a thereon in alignment with the markings 2a 10 on the dial 2. The markings 2a and 14a refer, of course, to the kilocycle indicating marks by which the condenser is adjusted to receive signals on different wave lengths.

Mounted around the spindle 12 one adjacent 15 each dial 14 are a plurality of contact discs 15. The latter are preferably split radially and are made of resilient conducting material. These discs are so mounted on the spindle that they engage it frictionally but may be independently 20 rotated provided the spindle is held while they are turned. Each disc 15 has an inturned extremity 15a which lies immediately in front of the dial 14 with which it cooperates, and also an outwardly projecting extremity 15b through 25 which a contact may be made in a manner hereinafter described. In the present embodiment the extremities 15a and 15b of each plate are positioned at substantially 180 degrees to one another.

On the spindle 12 a contact ring 16 is arranged, 30 and fixed on the said spindle is a pulley 17 to receive a belt 18 which also passes around a second pulley 19 fixed on the shaft of a motor 20.

A contact drum 21 is suitably supported in bearings as shown at 22 and 23, and is arranged substantially parallel with the spindle 12 and preferably on the same horizontal plane. Projecting from the periphery of the drum 21 and arranged progressively around the latter are a plurality of 35 resilient contact members 24 one being adapted to engage each of the disc extremities 15b. Fixed at one extremity of the drum is a ratchet wheel 25, and at the other extremity of the drum is a contact ring 26. Projecting outwardly beyond the latter is an extension shaft 21a integral with the drum 21 on the outer extremity of which a knob 21b is provided so that the drum may be turned manually. On the outer face of the knob 21b an indicating mark 21c is provided, which, 50 when the contact member 24 at the left end of the drum 21 is in position to engage its disc 15, is in alignment with a corresponding indicating mark 21e provided on the end wall of the cabinet A.

27 designates a source of power and 28 is a clock of any preferred type. The purpose of the latter is to provide a predetermined time lapse between the making of contacts in a manner hereinafter described. On the clock face a plurality of contacts 29 are provided which are wiped at intervals, in the present instance fifteen minute intervals, by the minute hand 30 to which a lead 31 is suitably connected.

10 32 denotes a magnet to one terminal of which a lead 33 is connected. The latter terminates at the clock face contacts 29. The opposite side of the magnet 32 is connected by a lead 34 to the source of power 27. The other terminal of the 15 latter is connected to the lead 31 and thus to the minute hand 30.

Arranged adjacent the magnet 32 so as to be moved axially thereby is a plunger 54 which is horizontally slideable in a bearing 55. A dog 35 20 is pivotally supported by the plunger 54, and a spring 36 is so arranged as to tend to force the outer extremity of the dog downwardly into engagement with the teeth of the ratchet wheel 25. A helical spring 37 is so mounted around the plunger 54 as to tend to hold the latter spaced 25 from the magnet 32. Thus when the magnet is energized the plunger 54 and dog 35 are moved towards it, and as soon as the current flow to the magnet ceases the spring 37 returns the plunger 30 to its initial spaced position and causes the dog 35 to turn the ratchet wheel one tooth. In this manner the drum 21 is so turned that the resilient members 24 are successively so positioned as to be engaged by one of the contact discs 15 by its extremity 15b.

35 From leads 31 and 34 other leads 38 and 39 respectively extend and are connected to the motor 20. The latter, however, normally fails to rotate due to a shunt connection. The latter consists 40 of the following: From the leads 38 a wire 40 extends to brushes 41 which wipe the contact ring 16; and from the lead 34, between the source of current 27 and the lead 39, another wire 42 is provided which terminates in brushes 43 which wipe the contact ring 26. Between the brushes 43 and the lead 34 a resistance 44 is inserted in the wire 42.

50 Contact between the rings 16 and 26 is normally made through the spindle 12, one of the contact discs 15, its cooperating contact member 24, and the drum 21. However as soon as the drum is rotated by the ratchet wheel 25, plunger 54 and magnet 32 the connection between all the discs 15 and members 24 is broken and consequently 55 the motor commences to operate and turns the spindle 12 until the extremity 15b of the next disc 15 has been brought into contact with its member 24 which has meanwhile been brought into 60 contacting position by the ratchet wheel 25. Then the shunt connection is again completed and the motor is again rendered inoperative.

65 The operation of the device is briefly as follows: The dial 2 is first turned so that the station whose program is then desired is being received. Then the left hand disc 15 is turned horizontally with its extremity 15b in position to engage its contact member 24, when it will be found that the pointer 15a on that disc points to the wave length of the 70 station whose signal is being received. The knob mark 21c must then be positioned, by rotation of the knob 21b, to register with the indicating mark 21e. Thus the drum is so turned that its contact member 24 is in engagement with the left hand disc extremity 15b. The shunt connection here-

5 inbefore described is then completed and a switch 50 so arranged in the wiring as to control the magnet, motor and shunt circuits is then closed. The discs in order from the left are then turned so that their pointers 15a register with the wave 10 lengths on their dials of the stations whose programs are desired at fifteen minute intervals from that time, or from the next quarter-hour. Obviously when a station is to be listened to for a longer period two or more consecutive discs 15 are similarly set. Care must be taken that when the discs 15 are being turned that the dials 14 are held against rotation.

15 Obviously the number of programs for which automatic setting is provided depends entirely upon the number of discs 15, contact members 24, and dials 14 provided. The number of teeth in the ratchet wheel 25 must of course correspond to the number of disc and member contacts.

20 While in the foregoing the preferred embodiment of the invention has been described and shown, it is understood that the construction is susceptible to such alterations and modifications as fall within the scope of the appended claims.

25 What I claim is:

1. In an arrangement of the character described, the combination of a variable condenser, a shaft therein by the rotation of which said condenser is adjusted to receive signals on different wave lengths, a spindle connected to said shaft 30 so that they rotate together, a plurality of discs on said spindle which normally rotate with the latter, a drum, contact members arranged spirally around the periphery of said drum, each member being adapted to make an electrical connection 35 with one of said discs, electrical time controlled means for turning said drum so that each member in turn is so positioned as to be engaged by one of said discs, and means turning said spindle when the drum is turned so that another disc is 40 brought into engagement with its contact member.

2. In an arrangement of the character described, the combination of a spindle connected to the shaft of a variable condenser so that the 45 spindle and shaft turn together at uniform speed, said condenser having a dial thereon which turns with its shaft, a plurality of spaced dials on said spindle, a plurality of discs on said spindle one adjacent each of the dials thereon, each disc having an inturned portion which forms a pointer 50 and lies adjacent the periphery of its dial, each disc having an outwardly projecting extremity, a drum rotatably supported substantially parallel with said spindle, a plurality of contact members extending from its periphery in stepped relationship to one another, each member being adapted to engage one of said disc extremities and make an electrical contact therewith, means for turning said drum a portion of a revolution at 60 predetermined intervals so that another member becomes so positioned as to be contacted by a disc extremity, an electric motor, means for rotating said spindle from said motor, and a shunt circuit completed through engagement of one of 65 said discs with their cooperating members to prevent operation of said motor.

3. In an arrangement of the character described, the combination of a spindle so connected to the shaft of a variable condenser that the spindle and shaft rotate at the same speed, a plurality of spaced dials fixed on said spindle, a plurality of discs in frictional engagement with said spindle one adjacent each dial, each disc having an outwardly projecting extremity, a pointer on 70

- each disc adjacent the periphery of its dial, a drum rotatably supported parallel with said spindle, contact members extending from the periphery of said drum each in alignment with one of said discs and adapted to make an electrical contact with the outwardly projecting extremity thereof, said members being arranged in stepped relationship to one another, means for intermittently turning said drum so that another member becomes so positioned as to be contacted by the disc opposite to it, an electric motor to turn said spindle, and a shunt circuit by which said motor is rendered inoperative when one of said members makes a contact with its disc.
- 5 4. In an arrangement of the character described, the combination of a variable condenser, a shaft therein by the rotation of which said condenser is adjusted to receive signals on different wave lengths, a spindle connected to said shaft, discs on said spindle normally turning with the latter but also independently rotatable thereon, a drum, resilient contact members on said drum each adapted to engage one of said discs, a time controlled means including an electric circuit for turning said drum so that one contact
- 10
- 15
- 20
- 25

member is moved into engagement with its disc, means in a separate circuit turning said spindle and a shunt connection in the circuit closed by contact of any one of said members with its disc for stopping rotation of the spindle.

5 5. In an arrangement of the character described, the combination of a variable condenser, a shaft therein by the rotation of which said condenser is adjusted to receive signals on different wave lengths, a spindle connected to said shaft, a plurality of dials on said shaft each having markings thereon to indicate the setting of the condenser, a plurality of discs on said spindle one adjacent each dial, each disc having a pointer thereon set in registry with the desired setting on the dial adjacent to it, a drum, a plurality of contact members thereon each adapted to contact one of the discs, electric time controlled means including an electric circuit for turning the drum so that one of the contact members engages its disc, means in a separate circuit for turning said spindle, and a shunt connection closed by contact of any one of said members with its disc for stopping the spindle rotation.

CHRISTIAN PETERSEN. 25
